UNITED STATES PATENT OFFICE.

JOHN DOWNE, OF SEATTLE, WASHINGTON.

CLOTHES-RACK.

1,260,163.

Specification of Letters Patent. Patented Mar. 19, 1918.

Application filed March 21, 1917. Serial No. 156,372.

To all whom it may concern:

Be it known that I, JOHN DOWNE, a citizen of the United States, and resident of the city of Seattle, county of King, and 5 State of Washington, have invented certain new and useful Improvements in Clothes-Racks, of which the following is a specification.

My invention relates to clothes driers and 10 consists of a drier having its parts so connected with each other and as a whole pivotally supported from a fixed body, that it may be folded into compact position and 15 swung into position of storage. The object of my invention is to provide a folding clothes drier so constructed that it may, when not in use, be compactly folded and placed within a recess provided for the 20 same in the wall of a room, and whereby, when wanted, it may be swung out of said recess and opened out into position of use.

My invention comprises certain novel features of construction and combinations of parts which will be described in the specification and then particularly defined by the 25 claims.

In the accompanying drawings I have shown my invention in the form of construction which is now most preferred by me.

30 Figure 1 is a side elevation of my device when removed from its cabinet and opened out into position of use.

Fig. 2 is a top plan view of the device in like position of parts except that the rack 35 is therein shown by full lines, as swung into position parallel with the wall, and by dotted lines as extending outward perpendicular to the wall.

Fig. 3 is a sectional elevation taken just 40 within the outer standard or vertical frame, the direction of view being outwardly.

Fig. 4 is a side elevation of the same parts.

Fig. 5 is a horizontal section taken through the storage cabinet just above the clothes 45 rack, the latter being folded and stored within the opening in the cabinet.

Fig. 6 is a section taken on the line 6—6 of Fig. 3.

Fig. 7 is a transverse sectional elevation 50 taken through the inner half of the rack looking toward the inner end thereof.

Fig. 8 is a longitudinal section through the hand grip which is detachably securable to the controlling chain.

55 Figs. 9 and 10 are, respectively, elevation and plan views of the type of hinge em-

ployed for hinging the inner end of the rack to its cabinet.

Figs. 11 and 12 are side views from different view points of the fixture at the 60 upper end of the controlling bar which connects the various clothes supporting bars.

While my rack might be employed to advantage without combining the same with a wall cabinet, it would in most cases be so 65 employed and I have herein shown it as combined with a wall cabinet. Ordinarily the cabinet frame, herein indicated by the letter A, would be made as a complete 70 inclosing frame, of a size to fit between adjacent studs in a wall. The rack proper comprises two vertical standards or frames 1 and 2, the frame 1 being hinged to one side of the cabinet frame A, while the frame 2 is adapted to be drawn out and form the 75 post or supporting frame for the outer ends of the rack bars.

The inner post, or frame 1, is hinged by one edge to the casing or cabinet frame A, preferably by hinges which permit it to 80 swing bodily toward the rear end of the receiving chamber or outwardly therefrom, as is shown respectively in Figs. 5 and 1. A hinge which is suitable for securing this result, is shown in detail in Figs. 9 and 10. 85 This consists of the two leaves 10 and 11, which are secured respectively upon the casing frame A and upon the post or inner frame member 1. These two are pivotally connected by means of an intermediate 90 link 12.

Two bars 3 and 30 are pivoted upon the inner frame 1 respectively at the top and bottom thereof and in such manner that they may swing toward each other. The 95 hinges 31, by which they are connected with the post or inner frame member 1, permit the upper bar 3 to swing downwardly and the lower bar 30 to swing upwardly. These bars are so placed that they will not interfere with each other as they swing toward each other. The outer or swinging ends of these bars 3 and 30, are provided each with a roller 34, which roller is offset a short 100 distance away from the bar, both lengthwise and transversely thereof, as is clearly shown in Fig. 4. These rollers may be mounted upon bent bars 32 which are secured to the bars 3 and 30, as by staples 33.

The outer post or frame 2 has secured to 110 its inner surface two vertically placed bars 20, these being rabbeted upon the corner

next to the frame 2, so as to provide a channel 21, adapted to receive the roller 34 of one of these bars 3 and 30. These are shown clearly in Fig. 6, which also illustrates the relatively offset position of the two bars 3 and 30, whereby said bars will not interfere with each other during the folding operation.

The remainder of the bars which connect 10 the two vertical frames 1 and 2 are each made in two parts, 4, these being hinged by one end, each to its respective one of the frame members and by their other end to each other, as shown at 40. The hinging 15 of these two sections to each other and to the frame members 1 and 2, is such as will permit the central portion thereof to swing downward, or fold, when the frames 1 and 2 are brought closer together. To permit 20 this latter action, the two rigid bars 3 and 30 which connect the two frame members 1 and 2, must have their outer ends swing toward each other.

They should also be controlled in such 25 manner that the movement of the two will be equal in amount, to thereby maintain perpendicularity of the outer frame or post 2. This may be done by connecting the two bars by means of a chain, or like flexible conductor 51, which passes over guide pulleys 5 placed at the upper and lower part of the frame 2. To operate these to insure the beginning of the folding action, a second chain 52 may be applied, which is connected with the chain 51 or to one of the bars 3 or 30, and which passes over additional guide pulleys 50.

For convenience in applying a pull to this chain, a handle or grip 53 may be secured thereto. It may be desirable to have this handle grip adjustable in position along the chain. For this purpose I construct it as it is shown in detail in Fig. 8. This grip has a hole extending lengthwise 45 through it, through which passes the chain 52. It also has a spring-held catch 54 pivoted near one end thereof and having a finger 55 which is adapted to enter one of the links of the chain.

50 The upper bar 30 has secured thereto at the middle of its length a transverse bar or pin 43, which bar has pivotally secured thereto two or more vertical controlling bars 42. These bars are preferably provided 55 with metal clips or tips 44, these having holes 45 therein which are in the nature of slots to permit the slight movements of the pin 43 transversely of the bars 42. The vertical controlling bars 42 are pivotally 60 connected with the hinge 40 by which the

two sections of the bars 4 are connected. In consequence, all of these bars move in unison.

A simple and effective manner of pivoting the bars 4 to the vertical frames 1 and 2 is clearly shown in Figs. 5 and 6. This consists of using pivot supports with removable wire nails with their head ends bent at right angles to the body and having their points secured in the wood. These points may, however, be made screw threaded, which would insure better holding in the wood.

What I claim as my invention is:

1. A clothes rack having a vertically extending frame at both front and rear, a top bar and a bottom bar pivoted to one of said frames and having sliding connection with the other, and intermediate bars each composed of two half-length parts pivoted to each other and to said vertical frames. 75

2. A clothes rack as defined in claim 1 having a tie member pivotally connecting the two-part bars and one of the full length bars to insure their swinging together. 85

3. A clothes rack as defined in claim 1 having means connecting the swinging ends of its top and bottom bars to insure equal movements thereof in opposite directions. 90

4. A clothes rack as in claim 1 in combination with an endless chain thereon carried by one of the vertical frames and secured to said top and bottom bars to insure like movements therein in opposite directions. 95

5. A clothes rack comprising vertical end frames, clothes supporting bars composed each of two parts pivoted by an end, each to its respective end frame and by their other end to each other, a controlling bar pivotally connecting the common pivots of all said bars, and a rigid bar having pivotal connection with one end frame and with the controlling bar and a sliding connection with the other end frame. 100

6. A clothes rack having a vertically extending frame at both front and rear, a top bar and a bottom bar pivoted to one of said frames, channeled bars mounted upon the other of said frames, a rod carrying a roller secured to each of said top and bottom bars at their swinging ends at an angle to the axis of said bars, said rollers being adapted to be guided by said channeled bars, and intermediate bars each composed of two half-length parts pivoted to each other and to said vertical frames. 110

Signed at Seattle, Washington, this 14th day of March, 1917.

JOHN DOWNIE.
